UNITED STATES PATENT OFFICE.

MYRON W. WOOD, OF SIOUX CITY, IOWA.

FUEL-OIL BURNER.

Application filed June 3, 1924. Serial No. 717,597.

To all whom it may concern:

Be it known that I, MYRON W. Wood, a citizen of the United States, and a resident of Sioux City, in the county of Woodbury and State of Iowa, have invented certain new and useful Improvements in Fuel-Oil Burners, of which the following is a specification.

My present invention relates generally to burners and more particularly to gaseous fuel burners for oil burning furnaces employing kerosene and other known oil distillates, and the objects and advantages thereof will be hereinafter outlined and may be better understood after thorough description of the details of my improved construction and an explanation of its operation and uses.

In the accompanying drawing which illustrates my present invention and forms a part of this specification,

Figure 1 is a vertical section taken diametrically through my improved burner,

Figure 2 is a horizontal section taken substantially on line 2—2 of Figure 1, and

Figure 3 is a bottom perspective view of the lid or cover member.

Referring now to these figures my invention proposes a burner including an annular upwardly opening bowl-like body 10 having an enlarged central draft opening 11 vertically therethrough and having a lower outer annular shoulder 12 adapting the same to rest upon a flanged supporting ring 13. This ring in the practical use of the invention may rest upon the central portion of a furnace grate whose portion around the burner will of course be closed so as to confine the upwardly moving air currents to passage through the upright flue 11 of the bowl.

Into the base of the bowl leads a fuel oil supply pipe 14 and upwardly through the base of the bowl extends an overflow pipe 15 whose upper end terminates slightly below the upper edge of the bowl both as to its outer and inner walls, this overflow pipe having its upper end capped by means of a hood 16 in order to prevent clogging thereof in the presence of the gravel or small particles of fire resistant material of granular form with which the bowl 10 is filled.

Around the upper edge of the inner cylindrical wall 17 of the bowl 10 a ring shaped wick 18 is fixed as by means of a clamping

wire 19 so that the lower edge of the wick depends into the granular material with which the bowl is filled to a point below the upper end of the overflow pipe 15.

Seated upon the upper end of the inner wall 17 of the bowl is a circular cover 20 which may have an upper central handle 21 and which is provided with depending dividing webs 22 adapted to extend downwardly into the vertical air flue 11 in order to split the upwardly moving air current into several parts and thus insure an even distribution of this air current around the circumference of the cover. These webs or dividing walls 22 have shouldered portions 23 at their outer edges which form engaging lugs adapted to rest upon the upper edge of the inner cylindrical wall 17 of the bowl and in addition to the webs or walls 22 which split the air current, that portion of the undersurface of the cover 20 which projects partly over the bowl beyond the inner wall 17 forming the air flue, is pro-

vided with circumferentially spaced air deflecting lugs 24 and 25, the lugs 25 being located between the lugs 24 and being of different shape as compared thereto so that the divided currents of air passing across the top of the bowl are unevenly deflected in a downward direction toward the top of the bowl and in this way a thorough mixture of air and gas or vapor to form the combustible fuel, is assured.

In practice the bowl is filled with coarse gravel or broken particles of other fire resistant material, which being packed around the cap 16 of the overflow pipe, avoids all danger of displacement of said cap and does away with any danger of the overflow pipe becoming clogged. In starting the burner the flow of oil is turned on through the pipe 14 and the bowl is permitted to fill until the oil starts to overflow through the overflow pipe 15. At this time the lower edge of the annular wick 18 will be within the oil and the wick is then lighted by applying a match to its upper edge. The burning at the wick heats the material within the bowl and in fact heats up the entire burner and it is but a short space of time before generation of gas commences, the gas rising through the material with which the bowl is filled, beneath the outer peripheral portion of the cover 20. The drafts are

then turned on and the air rushing upwardly through the air flue 11, spreads out

between the depending walls 22 and rushes outwardly to mingle with the gas and in this way form a thorough mixture for practically perfect combustion beyond the external edge of the burner. It is desired, however, to call particular attention to certain features and advantages in use as follows.

My improved burner as a whole is entirely safe in use because no matter how open the drafts are or how great or sudden the changes in draft from any cause, the fire will not go out as is common with other makes of burners. My improved device continues to burn for some few minutes after the oil is shut off and by the time gas ceases to form and the fire goes out, the temperature of the burner is lowered to such an extent that even if the oil were immediately turned on there would not be enough heat in the burner to generate gas and hence it would be impossible for explosion on the accidental application of a light to the burner as for instance careless dropping of a lighted match into the furnace.

In view of the fact that after operation of the burner commences the flame starts from substantially beyond the center of the burner, in fact beyond the outer edge of the burner, a flame of a certain length will play just that much closer to the sides of the fire pot of a furnace than is the case where oil is fed in the center of the burner. This results in the direct application of a substantially larger flame against the wall of the fire pot, making the burner very economical in the use of fuel.

By equipping the burner as outlined with a positive safe overflow pipe extending up within a short space below the top of the oil bowl and provided with a cap resting thereon which permits the oil to readily find its way into the upper end of the overflow tube, I insure against overflowing of the bowl. The cap of the overflow pipe or tube extends downwardly into the coarse gravel or other material of the wall to a sufficient extent to avoid any chance of the cap becoming displaced and the tube or pipe becoming clogged.

By equipping the cover with three air dividing walls on its underside, the air is forced to come out evenly all around the burner regardless of any side drafts or air

currents crossing the fire box, thus assuring an even flow of fire entirely around the burner and eliminating the possibility of carbon being formed through improper combustion. Proper efficient combustion is further assured by the lugs on the underside of the cover by means of which the air is unevenly deflected toward the bowl and thorough mixture with the gas is thus brought about. This also results in the elimination of vibration and noise ordinarily incident to burners of this type.

Altogether my invention proposes a burner which is simple, economical and highly efficient, as well as one which is lasting and durable and not only substantially fool proof but is also substantially trouble proof.

I claim:

1. A burner of the type described having an annular upwardly opening bowl and provided with a central vertical air flue and a liquid fuel supply opening into the base of the bowl, said bowl having an overflow means, a strip of material around the upper end of the air flue forming a wick, and a cover over the air flue for deflecting the air outwardly over the bowl.

2. A burner of the type described having an annular upwardly opening bowl provided with oil inlet and overflow means, said bowl including an inner wall forming therein a vertical air flue at the center of the bowl, and a cover over the upper end of the air flue having air dividing walls depending within the air flue and having a portion extending horizontally over the bowl, and a wick consisting of a strip of material secured around the upper outer edge of the said inner wall as described.

3. A burner of the type described having an annular upwardly opening bowl provided with oil inlet and overflow means, said bowl including an inner wall forming therein a vertical air flue at the center of the bowl, and a cover over the upper end of the air flue having air dividing walls depending within the air flue and having a portion extending horizontally over the bowl, said cover having a portion extending outwardly over the bowl and provided with air deflecting lugs arranged to unevenly deflect the air current downwardly toward the bowl.

MYRON W. WOOD.
